DESIGN FOR A SHOE

Pasquale Borda, Brooklyn, N. Y., assignor to
Bancroft Walker Co., Waltham, Mass., a cor-
poration of Massachusetts

Application July 20, 1934, Serial No. 52,654

Term of patent 3½ years

To all whom it may concern:

Be it known that I, Pasquale Borda, a citizen of the United States, residing at 1448 85th St., Brooklyn, in the county of Kings and State of New York, have invented a new, original, and ornamental Design for a Shoe, of which the following is a specification, reference being had to the accompanying drawing, forming a part thereof, in which

Fig. 1 is a plan view of a shoe showing my new design, the outline being conventional and shown in dot and dash lines; and

Fig. 2 is a view of the shoe in side elevation.

The dominating feature of my design resides in a pattern of stitching contrasting in color to the plain background of the shoe and comprising a series of stitch lines running upwardly and rearwardly from a point near the forepart of the

shank on each side of the shoe, then looping forwardly and terminating in a pointed figure opposite the center of the throat of the vamp. The general outline of the pattern converges as it sweeps outwardly from the center of the vamp, then narrows to but two lines of stitching as it extends rearwardly in the sides of the vamp, then bulges in a segmental enlargement, then narrows again in the loop above mentioned, then widens in a tear-drop figure and finally terminates in a single line of stitching which extends to the sole line.

I claim:

The ornamental design for a shoe, substantially as shown and described.

In testimony whereof, I have affixed my signature hereto.

PASQUALE BORDA.
